UNITED STATES PATENT OFFICE.

RUDOLPH J. SCHWAB, CHARLES A. SERCOMB, AND JAMES K. TREMAIN, OF MILWAUKEE, WISCONSIN.

ENGINEER'S INSTRUCTOR.

SPECIFICATION forming part of Letters Patent No. 508,247, dated November 7, 1893.

Application filed May 24, 1890. Serial No. 353,025. (No model.)

To all whom it may concern:

Be it known that we, RUDOLPH J. SCHWAB, CHARLES A. SERCOMB, and JAMES K. TREMAIN, all of Milwaukee, in the county of Milwaukee, and in the State of Wisconsin, have invented certain new and useful Improvements in Engineers' Instructors; and we do hereby declare that the following is a full, clear, and exact description thereof.

Our invention relates to appliances for illustrating the mechanical action of steam engines, and our invention consists in certain peculiar and novel features of construction and arrangement, as hereinafter described and pointed out in the appended claim.

In order that our invention may be fully understood, we will proceed to describe it with reference to the accompanying drawings, in which—

Figure 1 is a side elevation of a machine constructed in accordance with our invention. Fig. 2 is a plan view of the same. Fig. 3 is a side elevation of the link-motion and the adjacent part of the supporting frame therefor; this view being partly in section on the line 3—3 of Fig. 2. Fig. 4 is a similar view of the reverse side of the cylinder, steam-chest, and guide portions of the machine. Fig. 5 is a transverse vertical section on the line 5—5 of Fig. 4. Fig. 6 is an oblique cross-section on the line 6—6 of Fig. 3.

The objects of our invention are, to produce a working diagram-model which shall clearly illustrate the construction, arrangement and actual movements of the various parts of a locomotive engine, and also the various adjustments of the reversing-lever and link-motion necessary to reverse the engine, and to vary the lead of the valve so as to control the steam cut-off and exhaust. These objects we attain by virtue of the construction which we will now proceed to describe.

In the drawings A designates the base of the machine upon which the frame-work which supports the moving parts is mounted. This frame-work is preferably composed of two flat elongated vertical sections B, C, connected together at the lower and upper parts respectively of their contiguous ends by screw-bolts D and E, as shown in Figs. 1 and 2. At

its outer end the section B is formed with a vertical extension F having a central horizontal cross-piece f, and, at its upper end, a segmental slot f'. Adjacent to the inner side 55 of this vertical extension F is formed a second vertical extension G, and at the inner end of the frame-section B is formed a vertical L-shaped extension H. Upon the cross-piece f is pivoted the lower end of a lever I 60 which carries at its upper portion a set-screw i the stem of which works through the segmental slot f'. A link J is connected at its rear end to the lever I at a point between its pivot and its set-screw i and the front end of 65 this lever is connected to the upper arm k of a bell-crank lever K. This bell-crank lever is pivoted upon a stud k² at the inner upper corner of the extension H. The opposite arm k' of lever K is pivotally connected to the 70 upper end of a link L, the lower end of which is pivoted to a bridge-piece m' spanning the segmental slot of the quadrant-link M.

The extension G is formed with a boss g which forms the bearing for a short shaft N 75 upon the front end of which is cast, keyed or otherwise similarly secured a wheel O, which is thus adjacent to the front side of the frame section B. That part of the shaft N which protrudes beyond the rear side of the frame-extension G is supported in a bearing G' rising from section B, and carries two eccentrics P, P', the straps p, p', of which are connected by rods p², p³, respectively with the lower and upper parts of the quadrant-link M. From 80 this description it will be seen that the frame-section B and the movable parts carried thereby closely simulate the carrying and controlling parts of a locomotive engine. For example, the wheel O represents one of the 85 drivers of the engine, N one of the driving axles, P, P', the usual eccentrics of the main driving axle; L the usual link hanger; K one of the usual lifting arms, and I the usual reversing lever, &c.

The outer end of the frame-section C is formed at its base with two wheel-like portions c, c, and immediately above these portions with a rearwardly sunken horizontally elongated panel Q. Above this latter portion 90 Q is formed an approximately oblong rectangular horizontal extension R. A horizontal

portion S, containing a longitudinal slot s, connects the middle of the inner end of portion Q with the inner end of the frame-section C, and the upper corner of the inner end 5 of this section C is formed with an offset c'. Upon this off-set c' is pivoted a rocking lever S' the lower end of which is pivotally connected to a block m in the quadrant-link M. The portion Q of the frame-section C is de-
 10 signed to simulate a steam cylinder, divided longitudinally, and the portion R of said section is likewise designed to simulate a steam-chest. A hole t at the juncture of the portions Q and R represents the exhaust port; 15 curved grooves t', t'', represent the inlet ports from the steam-chest to the cylinder and a groove t³ in the upper part of the front side of portion R represents the balance port. A flat plate U slides across the portion R and 20 is formed to simulate a "D" or slide-valve, and an extension u of one end of the plate U represents the valve stem. This extension u works through an off-set u' formed on the inner edge of the portion R to represent the usual stuffing box, and the outer end of said extension is connected to a rod V which represents the usual valve rod. The opposite end of this rod is pivotally connected to the upper end of the rocking-lever S'. A flat 25 plate W which slides across the portion Q of the frame-section is formed to simulate the usual piston-head and an extension w of this plate represents the usual piston-rod. This rod works through an off-set r representing the usual stuffing box of the cylinder and to the outer end of this extension w is pivotally connected one end of a bar X which represents one of the main driving rods of a locomotive engine. The opposite end of this 30 bar X surrounds a pin o on the wheel O, said pin serving as a handle by which the wheel is turned to operate the moving parts of the machine. A lug w' projects through the slot s and a pin w² passes vertically through this 35 lug and serves to retain the extension w and plate W in proper relation to the adjacent parts of the frame-section C during the movements of said plate and extension. A lug u² projects similarly through a slot u⁵ in the portion R, and carries a pin u³ which retains the extension u and plate U in proper working 40 position relative to the part R of the frame-section C. A spring y is secured at its lower end in a lug Y upon the reverse side of the 45 frame-portion Q and the upper end of this spring is struck by an extension u⁴ on lug u² as the plate U is moved back and forth. The 50 relative positions of these parts are such that when the plate arrives at the "exhaust 55 points" of its movements the spring y will

be vibrated by said extension u⁴ and thus give an audible report of the exhaust.

From the above description it will be seen that we have produced a machine (which we call an "instructor") the various parts of 65 which bear close resemblance and occupy analogous positions to the operative parts of a locomotive engine. This machine, consequently, serves as a valuable adjunct to the training of locomotive engineers or others 70 desiring to educate themselves for that business.

A very important feature of our device lies in the adjustable connections between the eccentric-straps p p' and rods p² p³, best shown 75 in Fig. 3, said straps having grooved extensions p⁴, and the adjacent ends of the rods p² p³ being provided with slots p⁵, so as to be adjustably held at any desired point within the grooved extensions p⁴, by set-screws p⁶, 80 and thereby to equalize the travel of the "slide-valve" or flat-plate U, over the grooves t' t² which represent the steam ports.

Our device belongs to that class of inventions which includes Patent No. 461,772, granted 85 to Miller and Hill, known as "link-valve-motion models" and like that device ours is intended to produce an audible sound, though by somewhat different means.

Having thus described our invention, what 90 we claim as new therein, and desire to secure by Letters Patent, is—

In an improved educational appliance, consisting of a working diagrammatic model of an engine, the moving parts of such engine being simulated by moving parts of the model, the combination of a rearwardly sunken horizontally elongated panel, with an approximately oblong rectangular horizontal extension, provided with a longitudinal groove on one side 95 with a slot through said groove, a flat spring secured edgewise to the rear side of said panel and projecting up in line with said slot, and an arm connected to the described moving parts of the device, and sliding in said groove, 100 and carrying a pin projecting through said slot and intermittently in contact with the top edge of said spring, substantially as set forth.

In testimony that we claim the foregoing we 105 have hereunto set our hands, at Milwaukee, in the county of Milwaukee and State of Wisconsin, in the presence of two witnesses.

RUDOLPH J. SCHWAB.
CHARLES A. SERCOMB.
JAMES K. TREMAIN.
